(57) **CLAIM**

The ornamental design for a PVC flooring as shown and described.

DESCRIPTION

FIG. 1 is a perspective top view of a portion of the PVC flooring, in accordance with the design;

FIG. 2 is a detailed perspective top view of enlargement area 2 in FIG. 1; and,

FIG. 3 is a detailed perspective top view of enlargement area 3 in FIG. 1.

The PVC flooring includes evenly spaced broken lines depicting portions of the PVC flooring that form no part of the claimed design. Dot-dot-dash broken lines in PVC flooring designate a symbolic break along its length of the PVC flooring, in which the dot-dot-dash lines, the bracket, and the area of the symbolic break depicted by the dot-dot-dash broken line and bracket form no part of the claimed design.
